UNITED STATES PATENT OFFICE.

WALTHER HIBY, OF NOORDWIJK AAN ZEE, NETHERLANDS, ASSIGNOR TO JOHAN CHRISTIAAN BARON VAN HAERSOLTE VAN HAERST, OF DRIEBERGEN, NETHERLANDS.

CONSTRUCTION OF HORIZONTAL COKE OVENS WITH REGENERATORS.

Application filed July 13, 1920. Serial No. 396,008.

To all whom it may concern:

Be it known that I, WALTHER HIBY, a subject of the German Republic, residing at Noordwijk aan Zee, the Netherlands, have 5 invented certain new and useful Improvements in the Construction of Horizontal Coke Ovens with Regenerators (for which I filed an application in Germany Aug. 15, 1916), of which the following is a specification.

The present invention relates to regenerative-coke-ovens, the regenerators of which are underneath the floor of the ovens and arranged in the direction of the length of 15 the individual oven and in which ovens the even and odd-numbered flues are alternately directly heated. In these ovens the heating gas is led first into the first, third, fifth, etc., heating flue and burns upwardly, and the 20 burnt gases pass downwardly into the second, fourth, and sixth, etc., flue. After the reversal of the direction of heating, about every 30 minutes, the heating gases are supplied to the second, fourth, sixth, etc., flues 25 and burn upwardly and the burnt gases descend into the first, third, fifth, etc., heating flue. In these constructions the air is admitted for the total length of one oven at one time on the left side of the oven and the 30 combustion products travel to the right side towards the chimney and the next time after reversing the air is admitted on the right side and the products of combustion travel on the left side to the chimney. In ovens 35 of this kind the gas is introduced by burners of special width, while the distribution of the air, commonly introduced through one or two sole-flues, is generally regulated by dampers at the upper end of the vertical flues. It is found by experience that these 40 dampers should be placed in such a way, that the damper openings are widest at the end of the oven where the air enters and narrowest at the end towards the chimney. 45 In ovens when the draught-direction is reversed from time to time these dampers are correctly placed for the distribution of the air when flowing in one direction but are incorrectly placed for the opposite direction. 50 The present invention avoids this objection and in coke-ovens built accordingly the air is always admitted from one side and the waste-heat goes always to the other side.

In the accompanying drawings Figs. A, B

C and D the invention is shown in connection with sub-heated regenerative-coke-ovens with vertical heating-flues, where the regenerators are placed between the soles of the ovens and the arches of the substructure and in which ovens the flues are directly heated alternately in the even- and uneven-numbered heating-flues.

Figure A is a vertical longitudinal section of the coke oven, the plane of the section passing thru a heating wall;

Fig. B is a transverse section taken on lines BB and CC of Fig. A;

Fig. C is a horizontal transverse section taken on lines DD and EE of Fig. A;

Fig. D is a sectional detail of a modified form.

Between the oven-chambers 1 are located the heating-walls 2 with the uneven-numbered flues 3 and the even-numbered flues 4; to each flue 3 corresponds a burner pipe 5 and to each flue 4 a burner pipe 6. The burner pipes 5 and 6 receive gas from gas-pipes in the sub-ways underneath the ovens and they discharge the gas into the heating flues at the height of the floor of the ovens. In the construction, shown on the drawing, each regenerator is subdivided by a number of partition-walls into small checkerwork-chambers, but this is not material as the transverse partition-walls may be omitted. According to the drawing each heating flue 3 with burner 5 has a checker-work-chamber 7 and each heating flue 4 with burner 6 a checker-work-chamber 8.

The chambers 7 and 8 lie always in pairs underneath the floor of one oven and they are separated by the heavy supporting structure for the oven walls. The chambers 7 receive air or deliver the waste-heat through sole-flues 9, the chambers 8 through sole-flues 10. Each sole-flue 9 has an air-admission-valve 11 and a waste-heat-outlet-valve 13; each sole-flue 10 has valves 12 and 14 respectively. All the valves for gas and air are operated by one common-reversing mechanism.

In the position of the reversing mechanism, shown on the drawing, the gas is admitted through burners 5 and the air through valves 11, sole-flues 9, checker-work-chambers 7 into the heating-flues 3; the waste-heat escapes through flues 4, chambers 8, sole-flues 10, valves 14 to the stack-flue 15.

After a certain time the burner pipes as well as the air and waste-heat valves are reversed and then the gas enters through burners 6, the air through valves 12, sole flues 10, 5 chambers 8 to the flues 4; the waste-heat travels through flues 3, chambers 7, flues 9 and valves 13 to the main flue 15. The dampers 16 at the upper ends of the heating-flues 3 and 4 serve for the regulation of 10 the draft, that is also for the amount of air drawn in to each single flue and they are always in the right position for both draft directions in the heating-flues. As 15 the gas for each burner is introduced in a regulated quantity, the even and faultless heating of the whole length of the oven wall is assured. As shown in Fig. D, one may modify the construction as follows.

To avoid the great number of waste-heat 20 valves 13 and 14 a double main flue 18 and 18^a may be arranged conducting to the chimney, to which the connections 13^a, 14^a of the sole-flues 9 and 10 alternately correspond; in that case in each of the main-flues 18 and 25 18^a before the chimney a main reversing valve must be built, preferably with a water seal for effecting a perfect and tight closing.

In the form shown in Fig. A separate 30 valves 13, 14 controlling the discharge from the sole flues 9 and 10 are used, but in the form shown in Fig. D these valves are omitted and two separate flues 18 and 18^a are provided for the discharge from the sole 35 flues 9 and 10. Each main flue 18, 18^a is controlled by its valve.

Having now described my invention, what I claim as new and desire to secure by Letters-Patent is:

40 1. In a regenerative coke oven with vertical heating flues and in which the even and odd flues are alternately directly fired, the combination with said flues, of a plurality of gas burners, one burner for each of the even-numbered flues and another burner for each of the odd flues, a separate regenerator system for each group of burners, a sole flue underneath the regenerators of each system of regenerators and connecting with the lower 45 part of the regenerator chambers, an air inlet valve at one end of each sole flue and a waste heat outlet valve at the opposite end of each sole flue, the air inlet valves being located on one side and the waste heat outlet valves 50 on the other side of the oven structure.

55 2. In a regenerative coke oven with vertical heating flues and in which the even and odd flues are alternately directly fired, the combination with said flues, of a plurality of gas burner pipes, one pipe for each of the even numbered flues, thus forming a row of pipes for said flues, and another pipe for each of the odd flues, forming a row for said flues, a plurality of regenerators forming 60 a system for each set of flues, a sole flue un-

der the regenerators of each system of regenerators and connected with the lower part of the regenerator chambers, an air inlet valve at one end of each sole flue and a waste heat outlet valve at the opposite end of each 70 sole flue, the air inlet valves being located on one side and the waste heat outlet valves on the other side of the oven structure, a plurality of subways beneath the oven, gas mains in said subways connected to the gas 75 burner pipes, said regenerators and sole flues being located between the soles of the oven chambers and the ceilings of the subways.

3. In a regenerative coke oven with vertical heating flues and in which the even and odd flues are alternately directly fired, the combination with said flues, of a plurality of gas burner pipes for said flues, the pipes being divided into two sets, one set supplying the even-numbered flues of a heating wall and the other set supplying the odd-numbered flues of the said heating wall, a separate regenerating means for each set of flues, the regenerators extending lengthwise of the oven chamber, a longitudinal division wall separating the regenerator belonging to one of the regenerating means from the regenerator belonging to the other regenerating means, a sole flue connected to each regenerating means and supplied with 95 an air inlet valve at one end and a waste heat outlet valve at the opposite end, said flues extending from one end of the oven to the other and beneath the regenerating means.

4. In a regenerative coke oven with vertical heating flues and in which the even and odd flues are alternately directly fired, the combination with said flues, of a plurality of gas burner pipes for said flues, the pipes being divided into two sets, one set supplying the even-numbered flues of a heating wall and the other set supplying the odd-numbered flues of the said heating wall, a separate regenerator for each set of flues, the regenerators extending lengthwise of the oven 100 chambers, a longitudinal division wall separating the regenerator for one set of flues from the regenerator of the other set, there being at least two regenerators side by side, separated by the division wall and lying beneath the sole of the oven chamber, the gas burner pipes lying beneath the heating flues, sole flues connected to the respective regenerators and each supplied with an air inlet valve at one end and a waste heat outlet 110 valve at the opposite end and means for reversing the direction of the flow of heat thru the heating flues.

5. In a regenerative coke oven with vertical heating flues and in which the even and odd flues are alternatively directly fired, the even and odd flues being arranged in pairs, the flues of each pair being connected at the top, a valve for each of said connections, the combination with said flues and 125

valves, of a plurality of gas burner pipes for said flues, the pipes being divided into two sets, one set supplying the even-numbered flues of a heating wall and the other set supplying the odd-numbered flues of said heating wall, a separate regenerator for each set of flues, the regenerators extending lengthwise of the oven chambers, a longitudinal division wall separating the regenerator for 5 one set of flues from the regenerator of the other set, there being at least two regenera-
tors side by side, separated by the division wall and lying beneath the sole of the oven chamber, the gas burner pipes lying beneath the heating flues, sole flues connected to the 15 respective regenerators and each supplied with an air inlet valve at one end and a waste heat outlet valve at the opposite end and means for reversing the direction of the flow of heat thru the heating flues. 20

In testimony whereof I affix my signature.
WALTHER HIBY.
